UNITED STATES PATENT OFFICE

FREDERICK CHARLES RUPPEL, OF GRAND RAPIDS, MICHIGAN, ASSIGNOR TO W. B. JARVIS COMPANY, OF GRAND RAPIDS, MICHIGAN

CLOSURE FOR RADIATORS AND THE LIKE

Application filed December 18, 1929. Serial No. 414,890.

The main object of this invention is to provide a closure for radiators which is well adapted for use on radiators having the types of necks now in quite extensive use and one which is securely retained upon the neck.

A further object is to provide a structure having these advantages which may be very quickly applied to or mounted upon the neck.

Objects pertaining to details and economies of my invention will definitely appear from the description to follow. The invention is defined in the claims.

A structure which embodies the features of my invention is clearly illustrated in the accompanying drawing, in which:

Fig. 1 is a front perspective view of a radiator cap structure embodying the features of my invention.

Fig. 2 is a fragmentary view partially in vertical section on line 2—2 of Figs. 1 and 4.

Fig. 3 is an inverted view of the closure removed from the radiator neck.

Fig. 4 is a plan view of the neck, the coacting relation of the closure, keeper lugs and locking pin being indicated by dotted lines.

In the embodiment illustrated, 1 represents the radiator shell of a motor vehicle and 2 the radiator having a filling neck 3 projecting through the radiator shell. The neck is provided with an inturned flange 4 providing a seat for the gasket or packing 5. On the edge of the flange 1 form segmental, opposed cammed keepers 6 having depending stops 7 at corresponding ends thereof.

The closure body member 8 is chambered to receive the projecting end of the neck and rest upon the shell. The gasket 5 is clamped between the body member and the neck.

The body member 8 is provided with an annular depending flange-like latch member 9 having keeper engaging lugs 10 struck outwardly therefrom and engageable with the keepers by a rotative movement of the body member on the neck, thereby forcing the body member downwardly into clamping engagement with the gasket 5 and firmly seating it on the shell.

The body member is provided with an upwardly facing gasket seat 11 for the cap gasket 12. The locking pin 13 is arranged

through the bottom of the gasket seat to engage the stop end of one of the keepers 6; that is, it engages the end of the keeper in opposed relation to the lug, thereby locking the body member against rotative movement on the neck and preventing its removal without removing the locking pin.

The cap 14 is provided with a vertical pivot 15 mounted for vertical and rotative movement, the cap structure illustrated being that of the copending application of Frederick C. Ruppel and Michael B. Andrie. As the particular details of the cap do not constitute a part of this invention, they are not illustrated herein.

My improved closure is well adapted for use on radiator necks of the type now in extensive use, that is, radiator necks having cammed keepers with which the cap is directly engaged by a rotative movement.

My improvements provide a structure in which the cap is locked to the vehicle and an effective finish is provided for the shell.

I have illustrated and described my improvements in a very practical embodiment thereof. I have not attempted to illustrate or describe other adaptations or modifications as it is believed that this disclosure will enable the modification of my improvements as may be desired.

Having thus described my invention what I claim as new and desire to secure by Letters Patent is:

1. The combination of a neck having an inturned flange providing a gasket seat and having oppositely disposed segmental cammed keepers on the edge thereof, said keepers having stops at corresponding ends thereof, a gasket arranged on said neck, a closure body member chambered to receive the end of said neck and engaging said gasket thereon and having an annular latch member depending within the neck and provided with keeper engaging lugs struck outwardly therefrom, said body member being provided with an annular upwardly facing gasket seat, a locking pin arranged through the bottom of said upwardly facing gasket seat of said closure body member to engage the stop end of one of said keepers whereby the said closure body mem-

ber is locked against rotation on said neck, and a cap mounted on said body member.

2. The combination of a neck having oppositely disposed segmental cammed keepers, 5 said keepers having stops at corresponding ends thereof, a closure body member chambered to receive the end of said neck and having an annular latch member depending within the neck and provided with keeper engaging lugs struck outwardly therefrom, a locking pin arranged to lie in the path of and engage the stop end of one of said keepers whereby the said closure body member is positively locked against rotation on said neck, 10 and a cap mounted on said body member.

3. The combination of a neck having segmental cammed keepers, said keepers having stops at corresponding ends thereof, a gasket arranged on said neck, a closure member 20 engaging said gasket on said neck and provided with keeper engaging lugs coacting with said keepers on said neck, a locking pin on said body member lying in the path of and engaging the stop end of one of said 25 keepers whereby the closure body member is positively locked upon the neck, and a cap mounted on said body member.

4. The combination of a neck provided 30 with keepers, a closure body member provided with lugs engageable with said keepers by rotative movement of the body member, a gasket interposed between said body member and neck, said keepers being cammed so that the body member is clamped upon the gasket 35 by the engaging movement thereof, a locking pin on said body member lying in the path of and engaging one of said keepers in opposed relation to one of said body member lugs whereby the body member is positively locked 40 against rotation upon the neck, and a cap on said body member.

5. The combination of a neck provided 45 with keepers, a closure body member engageable with said keepers by rotative movement of the body member, said body member having an upwardly facing gasket seat, a locking pin arranged through the bottom of said upwardly facing gasket seat to lie in the path of and engage one of said keepers whereby 50 said closure body member is positively locked against rotation on said neck, a gasket arranged in said gasket seat over said pin, and a cap mounted on said body member to coact with said gasket.

6. The combination of a neck provided 55 with keepers having stops at corresponding ends thereof, a closure body member provided with keeper engaging lugs coacting with said keepers on said neck, a locking pin on said body member lying in the path of and engaging the stop end of one of said keepers whereby the closure body member is positively locked upon the neck, and a cap mounted on 60 said body member.

7. The combination of a neck provided

with keepers, a closure body member provided with lugs engageable with said keepers by rotative movement of the body member, a locking pin on said body member lying in the path of and engaging one of said keepers in 70 opposed relation to one of said body member lugs whereby the body member is positively locked against rotation upon the neck, and a cap on said body member.

In witness whereof I have hereunto set my 75 hand.

FREDERICK CHARLES RUPPEL.
